(57) **CLAIM**

We claim the ornamental design for the pair of decline weight arm assemblies for an exercise apparatus, as shown and described.

DESCRIPTION

FIG. 1 is a perspective view of a pair of decline weight arm assemblies for an exercise apparatus showing our new design;

FIG. 2 is a perspective view of the right hand weight arm assembly;

FIG. 3 is a side view of the right hand weight arm assembly;

FIG. 4 is a front view of the right hand weight arm assembly;

FIG. 5 is a perspective view of the left hand weight arm assembly;

FIG. 6 is a bottom perspective view of the left hand weight arm assembly;

FIG. 7 is an outside perspective view of the left hand weight arm assembly;

FIG. 8 is an inside perspective view of the left hand weight arm assembly; and,

FIG. 9 is a top perspective view of the left hand weight arm assembly.

The broken line showing of the exercise apparatus in FIG. 1 is included for the purpose of illustrating environmental structure and forms no part of the claimed design.
